UNITED STATES PATENT OFFICE.

BERTICE M. DIVER, OF INDIANAPOLIS, INDIANA.

DESIGN FOR AN AUTOMOBILE FENDER AND LAMP.

53,572.

Specification for Design.

Patented July 15, 1919.

Application filed March 24, 1919. Serial No. 284,882. Term of patent 14 years.

To all whom it may concern:

Be it known that I, BERTICE M. DIVER, a citizen of the United States of America, residing in the city of Indianapolis, county of Marion, and State of Indiana, have invented a new and original and ornamental Design for an Automobile Fender and Lamp, of which the following is a specification, reference being had to the accompanying drawings, forming a part thereof.

In the drawings, Figure 1 is a plan view of the automobile fender and lamp. Fig. 2 is a front elevation thereof. Fig. 3 is a side elevation thereof.

I claim:

The ornamental design for an automobile fender and lamp as shown.

BERTICE M. DIVER.
